UNITED STATES PATENT OFFICE.

FREDERICK E. HALL, OF CHICAGO, ILLINOIS, ASSIGNOR TO MILLER HALL & SON, OF CHICAGO, ILLINOIS, A CORPORATION OF ILLINOIS.

BEDSTEAD.

No. 902,820.

Specification of Letters Patent.

Patented Nov. 3, 1908.

Application filed June 19, 1908. Serial No. 439,380.

To all whom it may concern:

Be it known that I, FREDERICK E. HALL, a citizen of the United States, residing at Chicago, in the county of Cook and State of Illinois, have invented certain new and useful Improvements in Bedsteads, of which the following is a specification.

My invention relates to improvements in the means for fastening or securing together the parts of a metallic bedstead, especially the hollow rods or tubes of the head or foot boards. By the employment of my novel fastening or securing means, which constitutes a single hook-shaped rivet, I am enabled to hold together all parts of the head or foot of the bedstead. This single hook rivet is, of course, simple in construction and economical to produce, and when in place it is so neatly concealed as to be practically invisible.

On the accompanying drawing, which forms a part of this specification, I have illustrated a desirable embodiment of this invention, and on the drawing—

Figure 1 is an elevation of a head or foot board of a metallic bedstead; and Fig. 2 is a fragmentary elevation, partly in section, illustrating in detail and on an enlarged scale my improved fastening means for holding together the parts of the construction shown in Fig. 1.

The head or foot board has a main or principal hollow tube 10 bent to form the two parallel upright hollow corner posts 11 and 12, the intermediate section or portion 13 of the tube constituting the top rail or bar of the head or foot board. The device is also supplied with a tubular rail or bottom bar 14, the ends of which enter apertures 15 and 16 of the posts and extend inwardly to the interior of the posts. The bottom face of the middle or central section 13 of the bent tube 10 is provided with a plurality of apertures 17 extending into its hollow interior, the top face of the hollow rail or bar 14 being provided with holes 18 therethrough in alignment with the apertures 17. The bedstead is equipped with a plurality of hollow tubular upright spindles 19, the ends of which extend through the apertures 17 and 18 and preferably into the tubes 10 and 14 sufficiently so as to contact with their inner surfaces opposite the holes. The central hollow-spindle 19 at its upper end terminates somewhat short of the top inner surface of the tube 13, as is

clearly indicated in Fig. 2. Axially of this central spindle the bottom wall of the tube 14 is supplied with an aperture 20 for a purpose hereinafter indicated. Extended longitudinally of this central spindle, and disposed inside of the same, I provide a long rivet 21 having at its upper end a hook-shaped portion 22-23 which extends out of the upper end of the spindle 19 having the intermediate member 22 in contact with the upper wall of the tube 10, and the end of the extreme end portion 23 in contact with the lower wall of the tube 10. The bottom end of the rivet 21 extends through the aperture 20 and is headed over at 24 so as to firmly bind the parts of the head or foot board securely together, this head being so located on the under side of the rail or tube 14 as to be practically out of sight. By this simple means, that is by a single rivet or rod, I am enabled to securely and rigidly fasten together all the parts constituting the head or foot board.

The hook end 22-23 of the rod or rivet 21 is first passed through the aperture 17 in the bottom wall of the rail or tube 10, which is adapted to accommodate the end of the central or middle spindle. The upper ends of the various spindles are then inserted in the proper apertures 17, the lower rail or tube 14 is then brought to position so that its holes 18 will receive the bottom ends of the spindles, and then the post portions 11 and 12 of the bedstead are caused to approach each other so as to receive through the holes 15 and 16 the ends of the tube 14. Subsequently, the end of the rod or rivet 21 is headed at 24, which construction and assembling of parts causes a rigid and firm uniting thereof, without possibility or liability of displacement. If preferred, the heading of the rivet may occur prior to the insertion of the ends of tube 14 into the apertures of the upright posts.

Although I have shown and described a simple and economical construction for metallic bedsteads, it is to be understood that this invention is not limited and restricted to the precise and exact structural features set forth, because the invention may be used in many relations and the parts constituting the structure set forth may be varied in material respects without departure from the substance and essence of the invention.

I claim:

1. In a metallic bedstead, the combination

- of a pair of cross tubes one at least of which is transversely apertured, a hollow spindle disposed between said cross tubes and having one end fitted in said aperture, its other 5 end abutting against the other cross tube, and a rivet or rod located in said spindle and having one end extended out of that end of the tube passed through said aperture and abutting against opposite interior surfaces of 10 the cross tube, the other end of said rod or rivet being extended through and having means preventing withdrawal through the companion cross tube, substantially as described.
- 15 2. In a metallic bedstead, the combination of a pair of cross tubes apertured in alignment on their adjacent faces, one or more tubular spindles between said cross tubes and having their ends fitted in said apertures, and 20 a rivet or rod located in one of said spindles and having one end extended out of an end of its containing spindle and abutting against
- opposite interior surfaces of one of the cross tubes, the other end of said rivet or rod being extended transversely through the companion cross tube and headed at the exterior thereof, substantially as described. 25
3. In a metallic bedstead, the combination of one or more tubular spindles, a pair of cross tubes apertured to receive the opposite ends of said spindles, and a rivet or rod positioned in one of said spindles and having a hook-shaped portion at one end extended out of the containing spindle and abutting against opposite interior surfaces of one of said cross tubes, the other end of said rivet or rod being extended transversely through the companion cross tube and headed externally thereof, substantially as described. 30 35

FREDERICK E. HALL.
